UNITED STATES PATENT OFFICE

ERNEST Z. MUNZ, OF SPRINGFIELD, OHIO

SPRAYING DEVICE

Application filed September 16, 1929. Serial No. 393,024.

This invention relates to spraying devices, such as are used for spraying paint and the like, and is in the nature of an improvement upon the spraying device of the application for patent filed by me December 27, 1927, Serial No. 242,575.

The spraying device of the aforesaid application embodies auxiliary air jets to control the shape of the jet of liquid and one object of the present invention is to provide means whereby these auxiliary air jets may be so controlled as to regulate the size of the fan shaped spray produced thereby.

A further object of the invention is to provide a spray head having an air nozzle and means cooperating therewith to vary the size and shape of the auxiliary air outlets.

Other objects of the invention will appear as the device is described in detail.

In the accompanying drawing Fig. 1 is a longitudinal sectional view taken centrally through a spraying device embodying my invention, and partly in elevation; Fig. 2 is an end elevation of the spray head; Fig. 3 is a longitudinal sectional view of the spray head showing the cap adjusted to a position different from that shown in Fig. 1; Fig. 4 is an end view of a portion of the spray head showing the cap adjusted to impart to the auxiliary air outlets an intermediate size; Fig. 5 is a similar view showing the cap adjusted to impart to the auxiliary air jets a larger size; Fig. 6 is a plan view of the air nozzle and cap showing the means for retaining the cap in adjusted positions; Fig. 7 is a rear view of the cap; and Fig. 8 is a front elevation of the air nozzle with the cap removed.

In the drawing I have illustrated one embodiment of the invention and have shown the same as embodied in a spraying device corresponding in its main features of construction to the spraying device of the aforesaid application but it will be understood that this particular embodiment has been chosen for the purpose of illustration only, that the invention may take various forms and may be applied to spraying devices of various kinds.

The spraying device here illustrated comprises a supporting structure or main frame having a front portion 10 and a rear portion 11 connected one to the other by an intermediate arch or bridge 12. Mounted at the forward end of the supporting structure is a spray head comprising a body portion 13 having a reduced rear end portion 14 which extends through a suitable opening in the front end 10 of the supporting structure and is threaded to receive a nut 15 by means of which the spray head is secured to the supporting structure. The body portion 13 of the spray head has a longitudinal bore extending throughout its length and the intermediate portion of this bore is enlarged as shown at 16 to provide a liquid chamber which may be connected by a conduit 17, extending through a nipple 18, with any suitable source of supply for paint or other liquid to be sprayed. Mounted in the forward end of the body portion 14 is a liquid nozzle 19 having a tapered discharge opening to receive a needle valve 20 which is carried by a stem 21 extending rearwardly through the bore of the body portion 13 and having its rear end supported in a guide-way 22 in the rear part 11 of the supporting structure. A spring 23 acts on the stem 21 to move the same forwardly and hold the needle valve 20 to its seat.

Mounted on the body portion 13 of the spray head and arranged about the tapered end of the liquid nozzle 19 is an air nozzle 24 having in its front end an opening 25 arranged about the discharge end of the liquid nozzle and constituting a main air outlet which, when the liquid valve 20 is opened, will cause a jet of liquid to be discharged from the nozzle. The air nozzle is also provided with auxiliary air outlets which converge forwardly toward the axis of the liquid nozzle and are adapted to discharge jets of air against the jet of liquid and thus flatten the same and convert the jet into a fan shaped spray. In the present instance, I have shown two pairs of auxiliary air outlets, 26 and 27, the outlets of each pair being arranged on opposite sides of the main air outlet 25. The air nozzle is here shown as

having a frusto-conical forward end portion which is spaced from the tapered end of the liquid nozzle to provide an air chamber 28 which communicates with the main air outlet 25, and the auxiliary air outlets comprise grooves formed in the outer surface of the converging end wall of the air nozzle. A cap 29 is mounted about the outer surface of the air nozzle and closes the outer sides of the grooves 26 and 27 so as to convert the same into ports. This cap has a rearwardly extending portion which is mounted about a cylindrical part of the air nozzle and is retained thereon by a coupling member 30 which is screw threaded on to the body portion of the spray head. The grooves 26 and 27 are approximately semi-circular in cross section and in order to vary the size thereof and thus regulate the discharge of air therefrom the cap 29 is provided in its inner surface with one or more grooves adjacent to each of the grooves 26 and 27 and adapted to be moved into and out of registration therewith. In the present instance I have provided the cap with two grooves for each groove in the air nozzle, as shown at 31 and 32. The groove 31 is approximately semi-circular in cross section while the groove 32 is somewhat smaller than the groove 31. By rotating the cap 29 either the grooves 31, the grooves 32 or an adjacent ungrooved portion of the cap may be brought into line with the respective grooves 26 and 27. When the larger grooves 31 are in line with the grooves in the air nozzle the auxiliary outlet ports will be substantially cylindrical and will have a relatively large capacity, as shown in Fig. 5. When the smaller grooves 32 are in line with the grooves in the air nozzle the auxiliary outlet ports would be approximately elliptical in shape and will have a smaller capacity, as shown in Fig. 4. When ungrooved portions of the cap are in line with the grooves 26 and 27 the capacity of the grooves will be still further reduced and they will have an irregular shape, as shown in Fig. 2. It will be obvious that the larger jets of air will tend to flatten the jet of liquid to a greater extent than will the smaller air jets, thus imparting to the fan shaped spray a greater width than it will have when smaller jets of air are discharged against the same. In this manner the operator can control the width of the fan shaped spray to adapt it to the particular work in hand. The cap may be retained in adjusted positions in any suitable manner. In the present instance the rearwardly extending portion thereof has three notches 33 arranged to engage a stud or pin 34 carried by the cylindrical portion of the air nozzle. These notches 33 are so arranged with relation to the grooves in the cap that when any one of the notches is in engagement with the pin 34 the corresponding portions of the cap

will be in line with the respective grooves in the nozzle. To adjust the cap the coupling 30 is removed or screwed outwardly far enough to release the cap and after the cap has been adjusted and the coupling again tightened down the cap will be retained firmly in its adjusted position.

The body portion of the spray head is provided with longitudinal conduits leading from the respective air outlets to the rear end of the spray head where they are connected with other conduits in the supporting structure, which in turn may be connected with a suitable source of supply for air under pressure. As here shown, a main air conduit 35 leads from the air chamber 28, to the rear end of the spray head. The conduits 36 lead from the auxiliary outlets 26 to the rear end of the spray head, and other conduits, one of which is shown at 37, lead from the auxiliary air outlets 27 to the rear end of the spray head. The supporting structure has three conduits extending lengthwise thereof, as shown at 38, 39 and 40. In order to properly distribute the air from the conduits 38, 39 and 40 to the corresponding conduits in the spray head a distributor 41 is interposed between the spray head and the forward ends 10 of the supporting structure. This structure is of the type shown in the above mentioned application and need not be described in detail. Briefly it embodies a port to connect the conduit 38 with the conduit 35, and also embodies arcuate channels 42 and 43 which communicate respectively with the conduits 39 and 40 and are connected at the forward side of the distributor, respectively, with the conduits 36 and 37.

At the rear end of the supporting structure is an inlet air chamber 44 adapted to be connected with any suitable source of supply for air under pressure and with which the conduits 38, 39 and 40 are adapted to communicate. The connection between the air chamber 44 and three conduits is selectively controlled to enable air to be delivered to the main air outlet 25 alone or to permit air to be admitted to both the main air outlet and a selected pair of the auxiliary air outlets 26 and 27. The means for effecting this control is the same as that shown in the aforesaid application and consists in a rotary valve 45 so connected with the stem 21 of the liquid valve 20 as to be caused to rotate with that stem but to permit the stem to have longitudinal movement with relation thereto. Thus by rotating the stem the air may be admitted to the desired outlet port or ports and by moving the same lengthwise the liquid outlet may be opened or closed.

The stem is actuated by a lever or trigger 46. Pivotaly mounted on a collar 47 rigidly secured to the stem 21 and having its upper end arranged to fulcrum against a part 48 of the bridge 12 of the supporting struc-

ture, so that when rearward movement is imparted to the lower end of the lever rearward movement will be imparted to the valve stem and when transverse movement is imparted to the lever the selecting valve 45 will be adjusted. Preferably the part 48 of the bridge 12 is provided with notches 49 to receive the upper end of the lever and hold the same in adjusted positions.

10 While I have shown and described one embodiment of my invention I wish it to be understood that I do not desire to be limited to the details thereof as various modifications may occur to a person skilled in the art.

15 Having now fully described my invention, what I claim as new and desire to secure by Letters Patent, is:

1. In a spraying device of the character described, a spray head having a liquid nozzle, 20 a valve to control said nozzle, an air nozzle having a main air outlet arranged to cause a jet of liquid to be discharged from said liquid nozzle, said air nozzle also having a frusto-conical outer surface provided with 25 grooves converging forwardly toward the axis of said liquid nozzle, a cap mounted about said frusto-conical surface to close the outer sides of said grooves and form auxiliary air outlets, said cap having grooves adapted 30 to register with the respective first mentioned grooves and being adjustable to move the grooves therein into and out of registration with the respective first mentioned grooves to vary the size of said outlets, and means to 35 control the delivery of air to the several air outlets.

2. In a spraying device of the character described, a spray head having a liquid nozzle, 40 a valve to control said nozzle, an air nozzle having a main air outlet arranged to cause a jet of liquid to be discharged from said liquid nozzle, said air nozzle also having a frusto-conical outer surface provided with 45 grooves converging forwardly toward the axis of said liquid nozzle, a cap removably mounted about said frusto-conical surface to close the outer sides of said grooves and form auxiliary air outlets, said cap having 50 grooves adapted to register with the respective first mentioned grooves, means for securing 55 said cap on said air nozzle in positions to cause either said grooves or ungrooved portions of said cap to register with the respective first mentioned grooves, and means 60 to control the delivery of air to the several air outlets.

3. In a spraying device of the character described, a spray head having a liquid nozzle, 65 a valve to control said nozzle, an air nozzle having a main air outlet arranged to cause a jet of liquid to be discharged from said liquid nozzle, said air nozzle also having a frusto-conical outer surface provided with 70 grooves converging forwardly toward the axis of said liquid nozzle, a cap mounted

about said frusto-conical surface to close the outer sides of said grooves and form auxiliary air outlets, said cap having adjacent to each of said grooves a plurality of parts any one of which may be caused to register with the adjacent groove, each of said parts being so shaped as to impart a different size to the outlet formed by the groove with which it is in registration, and means to control the delivery of air to the several air outlets. 75

4. In a spraying device of the character described, a spray head having a liquid nozzle, 80 a valve to control said nozzle, an air nozzle having a main air outlet arranged to cause a jet of liquid to be discharged from said liquid nozzle, said air nozzle having a frusto-conical outer surface provided with two pairs of grooves, the grooves of each pair converging toward the axis of said liquid nozzle, 85 a cap mounted about said frusto-conical surface and having parts movable into and out of registration with the respective grooves to close the outer sides thereof and to form auxiliary air outlets and to control the size of said outlets, and selectively operable means 90 to control the delivery of air to said main air outlet and said auxiliary air outlets.

5. In a spraying device of the character described, a spray head having a liquid nozzle, 95 a valve to control said nozzle, an air nozzle having a main air outlet arranged to cause a jet of liquid to be discharged from said liquid nozzle, said air nozzle also having a frusto-conical outer surface provided with grooves 100 converging forwardly toward the axis of said liquid nozzle, a cap mounted about said frusto-conical surface to close the outer sides of said grooves and form auxiliary air outlets, said cap having grooves adapted to register 105 with the respective first mentioned grooves and being adjustable to move the grooves therein into and out of registration with the respective first mentioned grooves to vary the size of said outlet, said cap having notches 110 to engage a part fixed with relation to said air nozzle and retain said cap in its adjusted position, and means to control the delivery of air to the several air outlets.

In testimony whereof, I affix my signature hereto.

ERNEST Z. MUNZ.
